UNITED STATES PATENT OFFICE.

HENRY HASSENPLUG, OF HUNTINGDON, PENNSYLVANIA.

MECHANICAL MOVEMENT.

SPECIFICATION forming part of Letters Patent No. 235,432, dated December 14, 1880.

Application filed June 2, 1880. (No model.)

To all whom it may concern:

Be it known that I, HENRY HASSENPLUG, of Huntingdon, in the county of Huntingdon and State of Pennsylvania, have invented a new and Improved Mechanical Movement, of which the following is a specification.

Figure 1 is a side elevation of my improved mechanical movement. Fig. 2 is a partial side view of the same, showing the parts in a different position. Fig. 3 is a cross-section of same.

This invention relates to a new mechanical movement useful for propelling vehicles, driving machinery, and the like; and it consists of a new combination of parts for converting the rotary motion of a driving-shaft into oscillating motion of an elbow-lever, which oscillating motion is again converted into rotary motion of the driven shaft, the entire mechanism being readily reversible.

In the drawings, A is the driving-shaft, and B the shaft to be driven, both said shafts being hung in a suitable frame-work, C.

The shaft A carries a suitable crank-handle, b, for turning it, said crank-handle being preferably slotted, to be adjustable as to length and power. The shaft A carries also a toothed wheel, a, which is eccentric on the shaft, as shown, and which is between two toothed racks, c and d, formed above and below it on an elbow-lever, D, that is hung to the frame C at e. The distance between the racks c and d equals the double length of the larger radius of the eccentric-pinion a and exceeds the diameter of said pinion, so that upon being revolved the pinion will first gear into the rack c and then into the rack d, and so on, and never into both racks at once. By thus alternately gear-

ing into the racks c d the pinion will carry the one rack to the right and the other to the left, and thereby oscillate the lever D.

An arm, f, of the lever D connects by a rod, g, with a crank, h, of the shaft B, by which connection the oscillating motion of the lever D is converted into rotary motion of the shaft B. The motion of the shaft B will be reversed without reversing the motion of the shaft A, according as the crank h stands to the right or left of the shaft B when the operation of turning the shaft A commences. Thus, in the position shown in Fig. 1, if the shaft A is turned in the direction of the arrow 1, the lever D will first be moved in the direction of the arrow 2 and the shaft B turned in the direction of arrow 3, the rod g being first raised, and in this motion the shaft B will continue until arrested; but if at the commencement of operation the crank h and rod g were as in dotted lines in Fig. 1, the motion of shaft B would be reversed without reversing that of shaft A.

Great power and certainty of action are obtained by this mechanism.

I claim—

1. The combination of the shaft A and eccentric-pinion a with the pivoted lever D, having racks c and d, the distance between which exceeds the diameter of the eccentric-pinion, substantially as herein shown and described.

2. The combination of the shaft A, eccentric-pinion a, lever d, and its racks c and d with the rod g and crank-shaft B, substantially as herein shown and described.

HENRY HASSENPLUG.
